CLAIM

The ornamental design for a nestable bottle set, as shown and described.

DESCRIPTION

FIG. 1 is a front elevational view of a nestable bottle set comprising three nestable bottles according to my new design, shown in nested orientation;

FIG. 2 is a front elevational view thereof, with the nestable bottle set shown in an unnested orientation;

FIG. 3 is a bottom plan view thereof, with the nestable bottle set shown in an alternate unnested orientation; and,

FIG. 4 is a top plan view thereof.
